HOUSING STRUCTURE AND ITS
CONSTRUCTION

John A. Stromberg, Des Plaines, Ill.

Application September 16, 1935, Serial No. 40,664

3 Claims. (Cl. 189—36)

This invention relates generally to new and useful improvements in housing structures and their construction and has particular reference to low cost house construction wherein elimination of waste of materials, use of low cost materials, and minimum labor required for erection, are important factors.

Various attempts have been made to produce low cost housing by use of pre-fabricated wall units or pre-cast blocks of concrete, cinders and other materials, but such attempts have resulted in most instances with very little or no saving and with the objectionable inherent features that such structures have the appearance of temporary or portable structures and often present problems in sealing, joining and securing together such units. Furthermore, such pre-fabricated units were bound by physical limitations preventing wide and desirable variation in designs, plans and arrangements.

One of the objects of this invention is to provide new structural and constructional features which overcome the above-stated disadvantages and whereby attractive, durable or permanent housing is made possible at low cost through elimination of waste, use of low cost materials and reduction in time and labor required in the erection thereof.

Another object of the invention resides in the novel bent steel plate structural members and in their connections which can not only be fabricated at low cost but the use of which reduces waste of material and the time required in field assembly to a minimum. Such connections between the various metallic frame members being made without bolting, riveting or welding; the interconnecting or securing of the members together being accomplished solely by bending and interlocking portions during field assembly by means of a hammer.

With the above and other objects in view, my invention consists in the novel combination, construction and arrangement of the various parts and members shown in preferred embodiment in the attached drawings, described in the following specification and particularly pointed out in the appended claims.

In the drawings forming part hereof:

Fig. 1 is an illustration showing two vertical half cross-sections of a house embodying my invention; the left-hand cross-section being taken on line 1—1 of Fig. 2, and showing the steel framing and the right-hand cross-section being a similar opposite side cross-section showing the

cellular aggregate wall, floor, ceiling, and roof slabs;

Fig. 2 is a side elevation of an end portion of the house showing the steel frame before the walls are poured into place around same, but showing some of the roof slabs in place;

Fig. 3 is a cross-section taken on line 3—3 of Fig. 1;

Fig. 4 is a cross-section taken on line 4—4 of Fig. 1, showing roof slabs;

Fig. 5 is a cross-section of the wall taken on line 5—5 of Fig. 1;

Fig. 6 is a cross-section of a portion of the end wall taken on line 6—6 of Fig. 2;

Figs. 7, 8 and 9 are respectively, side elevation bottom view, and a cross-section taken on line 9—9 of Fig. 7, showing the connection of the roof channels at the ridge;

Fig. 10 is a section taken on line 10—10 of Fig. 12 showing the connection of the lower end of a roof channel with a longitudinal channel cap and channel wall stud;

Fig. 11 is a section taken on line 11—11 of Fig. 10;

Fig. 12 is a section taken on line 12—12 of Fig. 10;

Fig. 13 is a side elevation showing the connection of a horizontal floor or ceiling channel with the vertical channel wall stud;

Fig. 14 is a cross-section taken on line 14—14 of Fig. 13;

Fig. 15 is a cross-section taken on line 15—15 of Fig. 13;

Fig. 16 is a side elevational view of typical connection of the foot of a channel wall stud and a base plate showing the integral base plate anchors imbedded in a concrete footing;

Fig. 17 is an end view of the connection shown in Fig. 16;

Fig. 18 is a cross-section taken on line 18—18 of Fig. 17;

Fig. 19 is a plan view of the top of the base plate showing the manner of cutting same to form the connection portions.

Referring now to the illustrations shown particularly in Figs. 1 to 19 inclusive, the house here shown as an example of my invention, includes a steel frame consisting of a plurality of side wall studs comprising spaced channels 30 supported on base plates 31 and provided with longitudinal cap channels 32. The channel studs of the side walls are cross-connected by channel floor joists 33 and channel ceiling joists 34. The roof channels or rafters 35 are angularly disposed, as shown in Figs. 1 and 2, and connected together

at the ridge and also to the caps 32 and studs 30. The steel frame also includes end wall studs consisting of channels 36 which are secured to the floor and ceiling channels by clamps 37. The 5 bridging between the floor and ceiling channels consists of spaced pairs of flat bars 39 each extending longitudinally of the house and alternately over and under the channel joists.

I shall now proceed to describe the various 10 connections between the members above-stated.

In Figs. 7, 8 and 9, the connection of the channel rafters 35 at the roof ridge consists in an extended central web portion 35^A of one channel which extension is bent inwardly and 15 slotted as at 35^B to permit extension therethrough of a narrower web portion 35^C of the other channel 35. The web portion 35^C is then bent parallel to the portion 35^A to thus securely interlock the opposed rafters at the ridge.

The connection of the lower end of the rafters 35 with the channel plate or cap 32 and stud 30 is shown in Figs. 10, 11 and 12 and consists in recessing the rafter web, as at 35^D and bending a portion of the lower flange angularly as at 35^E 20 for support on the cap 32. A portion 30^A of the web of the stud channel 30 is extended to pass through a slotted opening 32^A of the cap 32 and through a slotted opening 35^F in the rafter 35 and then bent over the bent flange 35^E to securely 25 interlock the rafter, cap and stud.

Figs. 13, 14 and 15 illustrate the connection 30 between the horizontal floor or ceiling joists 33 and 34 and the wall studs 30 and consists in channellike openings 30^B in both flanges of the vertical studs 30; the lower end of the opening 30^B on the inner side of the building being enlarged as at 30^C and a portion of the flange being bent inwardly to form a support 30^D. The end portions of the flanges of each joist 33 and 34 are recessed inwardly from the edge, as at 38, 40 to decrease the width of the end portions of the flanges to permit the ends of the joists to be inserted through both flanges of the stud 30 for support on the bent flanged portion 30^D. The lower flange to be bent downwardly, as at 45 38^B, over the edge of the support 30^D to securely lock the joist to the stud.

It will be noted by reference to Figs. 7 to 15 inclusive that the illustrated connections consist in all cases of an integral extension of a defined portion of one of said members which is inserted through an opening or openings, respectively, in a like-defined portion of one or more of the other members of the frame work 55 and then bent to interlock or interconnect the members together. It will also be noted that such bent integral extensions are in all cases of less width than the portion from which they extend, and that when such bent integral extension is a portion of the web of one of the members it extends through the web or webs, respectively, of the other member or members and in the case of such bent integral extension being a portion of a flange of one of said members it therefore extends through the flange or flanges respectively of the other member or members, that is, in all connections either the web or flange portions of the members are interconnected.

The connection of the studs 30 to their base plates 31 is illustrated in Figs. 16 to 19 wherein the base plate 31 is fabricated from a single piece of sheet metal and consists of a substantially square plate formed with extended spaced integral anchors 31^A on two opposite sides of the

plate which are adapted to be embedded in the concrete foundation 40. The portions comprising the anchors being bent downwardly and outwardly to form L-shaped anchors. The plate 31 is punched or cut along lines as indicated in Fig. 19, to provide a pair of portions 31^B and 31^C which are adapted to be bent upwardly to positions shown in Fig. 17 to securely retain the lower end of the stud 30.

The portion 31^C is cut from within the general 10 configuration of portion 31^B and then bent right-angularly to engage the back of the web of the stud 30 as shown in Figs. 16, 17 and 18.

The free end of portion 31^B is slightly wider than the integral section to form spaced end portions 31^D adapted to be bent over a right-angularly bent web portion 30^E at the lower end of the stud; the portions 31^D being arranged to interfit closely between the flanges of the stud 30 and to engage the inner face of the stud web. As 20 clearly shown in Figs. 16, 17 and 18 the lower end of the stud is securely confined against movement in all directions.

The lateral bracing or bridging 39 shown in Figs. 1, 2 and 3 consists of spaced pairs of flat 25 bars extending longitudinally of the building across the joists 33 and 34 in such manner that each bar 39 alternately engages the upper and lower flanges of the spaced joists and the pairs of bars 39 also engaging opposite flanges of each 30 joist. Each of the bars 39 is formed with side portions 39^A and 39^B which are cut from the body of bar 39 and bent to form integral means adapted to securely clamp the bridging to the flange of the joists; the clamping portion 39^A 35 being bent angularly over the flange against the back of the web of the joist and the clamping portion 39^B being bent U-shaped to securely engage the outer and inner face of the flange of a joist as clearly shown in Fig. 3.

Referring now particularly to Figs. 1, 2 and 6, I will now describe the manner in which the end wall studs 39 are secured in place by means of clamps 37. The studs 36 are supported on the foundation 40 and secured to the floor and 45 ceiling joists and rafters by clamps 37. Each clamp consists of a flat twisted bar having ends bent U-shape to securely grip one flange of the stud 36 and one flange of the joist or rafter.

From the above description of the various 50 standard structural members and their connection one to the other, it will be apparent that the structural frame members can be readily pre-fabricated with such slotted and bendable portions that the members can be assembled and 55 erected at the site of installation into a substantially rigid frame without the use of bolts, rivets or welding and at a comparatively low cost due to the minimum of labor required.

Figs. 1, 2 and 4 illustrate the improved pre- 60 cast roof slabs 41 of cellular aggregate or other suitable material made in suitable widths and lengths to conform to the spacing of the rafters 35. As clearly shown in Fig. 4, these slabs 41 are designed to provide a support for the side 65 41^A upon the entire face of the upper flange of the rafter 35. The opposite side 41^B is provided with a depending portion 41^C which is supported upon the entire face of the lower flange of the 70 rafter 35. The depending portion is adapted to interfit between the rafter flanges and is therefore formed with angularly disposed faces 41^D, 41^E and 41^F. Above the face 41^F the slab is provided with an angular recess 41^G to permit the 75

side 41^A of an adjacent slab to reset upon the upper flange of the rafter.

The section shown in Fig. 6 shows a brick exterior finish.

5 The invention contemplates the use of cellular aggregate for the walls, floors and ceiling and the pouring of same at the site of installation in pre-fabricated steel forms which may be re-used on other construction projects of similar 10 kind.

10 It is also contemplated to build the interior partitions of any suitable fire-proof tiles and where the partition would carry any load to reinforce same with suitable metallic members 15 similar to the wall studs.

15 The cellular aggregate floors of 2½" to 3" thickness may be readily finished in tile, linoleum, wood or other suitable flooring. The interior of the walls may be finished in plaster or 20 constructed of other suitable interior finishes. The ceiling may be finished in tile or plaster on wire lath or in any suitable material. The exterior of the walls may be covered with brick, tiles, 25 wood or other suitable exterior covering. The various interior or exterior finishes are not shown in the drawings, except that Figs. 2 and 6 show a brick exterior in part.

25 In the ordinary small house of five to seven rooms, I prefer to use 4" x 1¾" x 1¾" channel 30 studs made from bent copper-bearing steel plate of about number 12 gauge and 8" x 2" x 2" channel joists and rafters of bent copper-bearing steel plate of number 10 or 12 gauge.

30 As shown in Figs. 5 and 6, the walls 51 consist 35 of poured cellular aggregate with spaced tubular passages 52 extending vertically of the wall. These passages may be arranged to extend from the basement to the roof to provide air ducts for controlled force draft for ventilating and cooling 40 purposes but they also obviously reduce the amount of the cellular aggregate used in such walls.

45 From the above description and attached drawings it will be readily apparent that the structural frame members constituting the steel skeleton are connected together by interframing portions of members within or through other members and interlocking the portions by hammer-bent sections to thus interlock the frame members without 50 the use of rivets, bolts or welding and to afford rapid and permanent assembly of the structural members at the site into a rigid skeleton.

55 While the illustrations show an adaption of the invention to a house, it is obviously adaptable to the construction of other structures and

buildings such as factories or various industrial buildings. The invention permits use of pre-fabricated steel and poured cellular aggregate walls in a manner to afford wide variation in architecture and individuality in design.

5 I am aware that various changes and modifications can be made in the details of construction without departing from the spirit or principles of this invention and I therefore do not wish to be understood as limiting myself to the exact details shown by way of example in the attached drawings. It is my intention to claim the invention as broadly as the state of the prior art will permit under the law of patents.

15 I claim:

1. In a metallic skeleton framework, a vertical channel stud having a web and flanged sides, one of the flanged sides having an aperture therein, a channel joist disposed angularly to said stud and having portions of the flanges 20 of its end cut to decrease their width to permit said end to be projected through said aperture in said stud, one of said flanges of decreased width being cut to permit a section thereof to be bent to thereby interlock said joist with said 25 stud.

2. In a metallic skeleton framework, a vertical channel stud having a web and flanged sides, one of the flanged sides having an aperture therein, a channel joist disposed angularly to 30 said stud and having portions of the flanges of its end cut to decrease their width to permit said end to be projected through said aperture in said stud, said stud having a portion of the apertured flange bent to form a support for the 35 end of the joist, one of said flanges of decreased width being cut to permit a section thereof to be bent over said stud bent portion to thereby interlock said joist with said stud.

3. In a metallic skeleton framework, a vertical 40 channel stud having a web and flanged sides, each of said stud flanged sides having an aperture therein, a channel joist disposed angularly to said stud and having portions of the flanges 45 of its end cut to decrease their width to permit said joist end to be projected through both of said stud apertures, said stud having a portion of one of the apertured flanges bent to form a support for the joist end, and one of the joist flange portions of decreased width being cut to 50 permit a section thereof to be bent over said stud bent portion to thereby interlock the joist with the stud.

JOHN A. STROMBERG. 55
